CLAIM

The ornamental design for a television receiver, as shown and described.

DESCRIPTION

FIG. 1 is a front perspective view of the television receiver showing our new design;
FIG. 2 is a front view thereof;
FIG. 3 is a back view thereof;
FIG. 4 is a left side view thereof;
FIG. 5 is a right side view thereof;
FIG. 6 is a top plan view thereof;
FIG. 7 is a bottom plan view thereof;
FIG. 8 is a back perspective view thereof;
FIG. 9 is a front perspective view, rotated 90 degrees in an alternate position;
FIG. 10 is a front view of FIG. 9;
FIG. 11 is a back view of FIG. 9;
FIG. 12 is a left side view of FIG. 9;
FIG. 13 is a right side view of FIG. 9;
FIG. 14 is a top plan view of FIG. 9;
FIG. 15 is a bottom plan view of FIG. 9; and,
FIG. 16 is a back perspective view of FIG. 9.
The broken lines depict portions of the television receiver that form no part of the claimed design.
